UNITED STATES PATENT OFFICE.

CHARLES ALBERT BOOTH, OF BRUNSWICK, MARYLAND.

VALVE CONSTRUCTION.

1,052,561.

Specification of Letters Patent. Patented Feb. 11, 1913.

Application filed May 2, 1912. Serial No. 694,728.

To all whom it may concern:

Be it known that I, CHARLES ALBERT BOOTH, a citizen of the United States, residing at Brunswick, in the county of Frederick and State of Maryland, have invented certain new and useful Improvements in Valve Construction; and I do hereby declare the following to be a full, clear, and exact description of the invention, such as will enable others skilled in the art to which it appertains to make and use the same.

My invention relates to new and useful improvements in valve construction and more particularly to that class known as rotating cut-off valves and designed particularly for use in connection with steam operated injectors.

My object is to provide a valve of this class which may be used in connection with the injector to release pressure between the injector and the check valve adjacent the boiler.

A further object is to so locate the valve that when the injector is in operation the exhaust pipe connected with the valve casting will be closed.

A further object is to so construct the valve that when the injector is not in use the passage from the injector to the boiler will be completely closed.

A further object is to so construct the valve that one of the openings communicating with the valve casing may be partially uncovered, while the other opening remains completely closed, and,

A further object is to provide means for operating the valve simultaneously with the operation of the injector.

Other objects and advantages will be hereinafter set forth and pointed out in the following specification.

In the accompanying drawings which are made a part of this application, Figure 1 is a side elevation of an injector showing my improved valve in section, and, Fig. 2 is an enlarged sectional view of my improved form of valve.

Referring to the drawings in which similar reference numerals designate corresponding parts throughout the several views, 1 indicates the injector which may be of the usual or any preferred type, such as is used for forcing water into a steam boiler and 2 indicates the lever employed for operating the injector, one end of the lever being pivoted to parts of the injector frame.

The injector is connected to a boiler (not shown) through the medium of a pipe 3, said pipe being provided with a check valve 4 adjacent the end thereof entering the boiler, said check valve being of the usual or well known type adapted to prevent the steam pressure in the boiler from entering the pipe. It frequently happens that the check valve 4, for various reasons, springs a leak so that the pressure within the pipe 3 is the same as the pressure within the boiler and when such is the case the injector will not properly work, as it is unable to overcome the pressure against the valves in the injector and for this reason I have provided my improved form of rotating or pressure regulating valve 5, which valve is mounted in a cylindrical casing 6 and said casing is connected with the pipe and injector through ports 7 and 8, respectively. The valve 5 is so arranged that when the injector is not in use the faces 9 and 10 thereof are seated over the ports 7 and 8, respectively, and completely close communication therethrough, so that should the check valve 4 spring a leak the pressure will be confined between the valves 4 and 5. The face 9 is of sufficient width as to snugly close the port 7, while the face 10 overlaps the port 8 to a greater extent whereby the port 7 will be partially opened previous to the opening of the port 8. By arranging the valve in this manner the pressure within the pipe 3 will pass into the upper portion of the casing 6 and through a central opening 11 in the valve 5 and thence through an exhaust pipe 12 communicating respectively with the lower portion of the casing 6 and the overflow pipe 13 of the injector, thus relieving the pressure in the pipe 3 and giving the jet of steam and water from the injector a clear passage through the pipe and permitting the same to travel with sufficient force to readily overcome the steam pressure within the boiler.

The valve 5 is operated from the lever 2 of the injector, the stem 14 of the valve projecting through one end of the casing 6 and having an arm 15 attached thereto which is in turn connected with a valve operating arm 16 of the injector by a link 17, the arm 16 being likewise connected to the lever 2 through a link 18, although any other preferred means may be employed for operating the valve 5 in conjunction with the lever 2. The valve 5 and the interior of the cas-

ing 6 are tapered from one end to the other so that the faces of the valve may be kept in perfect contact with the face of the casing and to accomplish this result a spiral spring 19 is introduced around the stem 14 and directs constant pressure against the valve to force it lengthwise and keep it in engagement with the casing.

In operating the injector the lever 2 is first thrown a short distance rearwardly to prime the injector, this operation rotating the valve 5 sufficiently to open the port 7, but not a sufficient distance to open the port 8 and if the check valve 4 should be leaking the pressure within the pipe 3 will be immediately released and permitted to pass through the opening 11 and exhaust pipe 12. As soon as the injector is properly primed the lever 2 is thrown open its full distance which will result in giving the valve 5 a half turn and positioning the face 9 over the end of the exhaust pipe 12, closing communication therethrough, while the opening 11 will be in direct alinement with the ports 7 and 8, thus giving a clear passage through the valve and pipe 3.

It will thus be seen that I have provided means whereby the objectionable features resulting from a leaky valve will be fully overcome and one that will insure the operation of the injector at all times. It will likewise be seen that in view of the simplicity of the valve it can be very cheaply constructed and readily applied to use. It will further be seen that, if desired, the valve can be located at a suitable point within the injector proper and it will further be seen that it can be successfully used in connection with other devices where pressure resulting from a leaky valve is to be overcome.

What I claim is:

1. A pressure regulating device comprising the combination with an injector, a check valve and a pipe connecting the injector and check valve, of a valve adapted to control the passage of particles through the pipe, one face of said valve having a greater overlap than the other, whereby when the valve is rotated the opening in one section of the pipe will be opened previous to the opening of the other section of the pipe.

2. In a pressure regulating device the combination with an injector, a check valve 55 and a pipe extending from the injector to the check valve, of a valve adapted to control the passage of particles through said pipe, said valve having an opening therethrough, a casing surrounding the valve 60 and having ports communicating with the openings of the pipe section, one face of the valve having a greater overlap than the opposite face, whereby when the valve is rotated one of the ports will be opened previous to the other and means co-operating with parts of the injector to operate said valve coincident with the operation of the injector.

3. A pressure regulating device, comprising a casing having ports therein, said casing being tapered, of a tapered valve adapted to enter said casing and be rotated to cover or uncover said ports, said valve having an opening therethrough one face of the valve overlapping its port a greater distance than the other, whereby one of the ports will be opened previous to the other port, means to direct pressure against the end of the valve to hold the same seated against the wall of the casing and means to rotate said valve.

4. A pressure regulating device comprising the combination with an injector having a lever to operate the same, a check valve 85 and a pipe connecting the injector with the check valve, of a valve casing having ports communicating with the openings in the pipe and injector, a valve seated in said casing and having an opening therethrough 90 said valve co-operating with said ports, one face of the valve overlapping its port a greater distance than the other, whereby one of the ports will be opened previous to the opening of the opposite port, an exhaust 95 port communicating with the valve casing and means connected with said lever to operate said valve when the lever is moved to operate the injector.

In testimony whereof I have signed my name to this specification in the presence of two subscribing witnesses.

CHAS. ALBERT BOOTH.
